UNITED STATES PATENT OFFICE.

GEORGE W. WHITE, OF MALDEN, MASSACHUSETTS.

IMPROVEMENT IN HOT-AIR FURNACES.

Specification forming part of Letters Patent No. **149,819**, dated April 14, 1874; application filed March 14, 1874.

To all whom it may concern:

Be it known that I, GEORGE W. WHITE, of Malden, in the county of Middlesex and State of Massachusetts, have invented an Improvement in Hot-Air Furnaces; and I do hereby declare that the following, taken in connection with the drawings which accompany and form part of this specification, is a description of my invention sufficient to enable those skilled in the art to practice it.

The invention relates to an improvement in hot-air furnaces, the improvement being particularly designed to increase the heat-radiating surface.

In my construction I combine with the dome of the fire-chamber (and, preferably, with an annular series of pipes leading from the bottom of said dome up into an annular pipe or chamber encompassing the top of the dome) an auxiliary annular pipe or chamber encompassing the fire-pot, said latter chamber being that into which the products of combustion finally pass before their exit through the main flue-pipe.

My invention consists, primarily, in combination with the furnace or fire-chamber dome, of the annular radiating pipe encompassing the fire-pot.

The drawing represents a construction embodying my invention.

Figure 1 shows the furnace in front elevation. Fig. 2 is a side elevation thereof. Fig. 3 is a plan, the upper radiator ring being removed.

a denotes the base; *b*, the ash-pit wall; *c*, the ash-pit door; *d*, the fire-pot plate or wall; *e*, the fire-pot door; *f*, the dome above the fire-pot. Extending horizontally from the bottom of the dome are seen the elbow-pipes *g*, such pipes bending and extending up to the radiator-ring *h*, that encompasses the upper part

of the dome, as seen in Figs. 1 and 2. This annular radiator connects with the main vertical flue-pipe *i*, as seen at *k*; but its connection therewith is controlled by a damper, *l*. Around the fire-pot *d* is placed the auxiliary radiator-ring *m*, said ring being joined to the ring *h* by vertical pipes *n n* and the flue-pipe *i*, the pipes *n n* leading from the ring *h* to the ring *m*, and the ring *m* opening into the main vertical flue-pipe *i*.

When the damper *l* is open, the products of combustion pass from the dome through the pipes *g* into the ring *h*, directly to and through the main flue *i*; but when the damper *l* is closed, the products of combustion pass from the annular pipe *h* down through the pipes *n n*, to the annular fire-pot radiator *m*, through which they pass to the vertical flue *i*.

As the auxiliary ring *m* is in the plane of the fire-pot, it is not only heated by the passage through it of the products of combustion, but is also heated by direct radiation from the fire-pot plate.

The connecting pipes *o* are placed at uniform distance apart, and such pipes, and the rings *h* and *m* and pipes *n n*, constitute a frame that can be set in any position upon the elbow-pipes *g*, to connect with a flue at either side, or at the back of the furnace, the changes of position being in accordance with the number of pipes *o*.

I claim—

In combination with the dome *f*, the annular radiator pipe *m*, located in the plane of the fire-pot, and connected by pipes *n* with the annular pipe *h*, surrounding the top of the dome, substantially as shown and described.

GEO. W. WHITE.
